UNITED STATES PATENT OFFICE.

DAVID REGINALD DAVIES, OF MANCHESTER, ENGLAND, ASSIGNOR TO WESTINGHOUSE ELECTRIC & MANUFACTURING COMPANY, A CORPORATION OF PENNSYLVANIA.

SWITCH CONTACT FOR CIRCUIT BREAKERS.

Application filed June 14, 1923. Serial No. 645,228.

This invention relates to electric switches, circuit closers and the like and has for its object to provide an improved contact member for such devices which shall have a large 5 current carrying capacity and at the same time be very flexible so as to permit of small movements or variations in the distance between the terminals of the switch or circuit closer when the circuit is closed and between 10 which it affords a means of connection.

Another object of my invention is to provide a switch contact device that is particularly well adapted for use in disconnecting switches associated with circuit breakers of 15 the truck panel type wherein fixed contact members, that are mounted within the truck cell, are engaged by contact members carried upon the truck when the truck is moved into the cell.

According to the invention, the improved contact member comprises a brush composed 20 of plates of good electrically conductive material, said plates being mounted so that one end of the brush makes contact by the edges 25 of the plates with one terminal of the switch, the other ends of the plates being adapted to make contact with the other terminal of the switch or circuit closer. The plates are arranged so that the pressure between the 30 two terminals of the switch or circuit closer when the circuit is closed is transmitted substantially in the direction of the longitudinal axes of the plates and, in order to secure flexibility and permit of slight movements of 35 the two terminals of the switch or circuit closer, the plates are curved so that the pressure between the contact surfaces tends to deform said plates and to spread apart the edges of the plates through which current is 40 transmitted.

In order that the nature of the invention may be clearly understood, a method of carrying out the same in practice will now be described as applied by way of example to 45 devices for making contact between electrical conductors one of which is moved towards and away from the other along an axis common to both conductors, as in the manner of disconnecting switch contacts of a standard 50 truck panel type circuit breaker.

Referring to the accompanying drawings, Figure 1 is an elevation of such a device

wherein the terminals of the device are shown in open circuit.

Fig. 2 is an elevation of the said device 55 wherein the terminals are shown in closed circuit and,

Fig. 3 is a separate view of the improved contact.

Referring now to Fig. 1, two electrical 60 conductors 1 and 12 are shown between which it is desired to make electrical contact. Where the contact conductors are used as a disconnecting switch, member of a truck panel type circuit breaker, the conductor 1 is preferably carried upon the circuit breaker truck and the conductor 12 is 65 mounted within the truck cell in alinement with the conductor 1. By reason of this arrangement, the contact elements mounted on 70 the conductor 1 are withdrawn from the cell with the truck and may readily be inspected and repaired. The conductor 1 is provided with a contact block 2 on which is mounted the improved contact member (shown separately in Fig. 3) comprising two brushes 3 and 4 formed of a plurality of plates or 75 laminations or copper or any other suitable metal bent to any suitable curve. The plates are secured by means of screws 7 and 8 to 80 the opposite sides of a support 5 and are so arranged that the chord of the arc to which they are bent is parallel with the direction of movement of the movable conductor 1, that is to say in a horizontal direction as shown in the drawings. Suitable 85 springs 9 and 10 are interposed between the heads of the screws and the sides of the brushes.

The support 5 is mounted on the contact 90 block 2 of the conductor 1 by a bolt 6 passing longitudinally therethrough on which said support can slide and the brushes 3 and 4 are held with one end of each in contact with the face of the contact block 2. The 95 conductor 12 is provided with a contact block 11 having a plane contact face perpendicular to the direction of movement of said conductor and adapted to make contact with the exposed edges of the two brushes.

The operation of the switch or circuit closer is as follows:

When the conductor 1 is moved to the left as shown in Fig. 2 to close the circuit, the

edges of the plates or laminations are pressed hard against the plane faces of the contact blocks 2 and 11 and the plates then spread outwards to a small degree, causing what is known as a "wiping" contact. At the same time, the support 5 slides along the bolt 6 as shown in Fig. 2.

By the present invention, a contact member is provided which has a large current carrying capacity without at the same time being very bulky. Further, when the circuit is closed, a small amount of movement of the movable conductor may be made without opening the circuit, such movement only causing the edges of the plates of which the brushes are composed either to spread apart or close together slightly, the resistance to the passage of the current remaining substantially the same. Other advantages of the improved contact will be evident and it is to be understood that the arrangement of parts is not to be restricted to that hereinbefore set forth since various modifications may be made without departing from the scope of the invention.

I claim as my invention:

1. Switch mechanism comprising a pair of relatively movable conductor plates and a flexible contact brush comprising flexible laminated plates disposed between the conductor plates and making yielding contact therewith, respectively, at opposite edges of the laminated plates and adapted to be flexed or bowed under tension when the conductor plates are moved into engagement with the brush.

2. Switch mechanism comprising a pair of relatively movable conductor plates and a flexible contact brush comprising flexible laminated plates bowed in the form of an arc and disposed between the plates in such manner that the chord of the arc is parallel with the plane in which the conductor plates are relatively movable and yieldingly mak-

ing contact with the conductor plates respectively at opposite edges of the laminated plates.

3. Switch mechanism comprising a pair of relatively movable conductor plates and a yielding contact member carried upon one of the conductor plates for longitudinal movement thereon and disposed between the conductor plates for making wiping conductive contact with the plates when the plates are moved toward each other.

4. Switch mechanism comprising a pair of relatively movable conductor plates and a yielding laminated conductive brush disposed in end to end relation to the contact plates and movably carried by one of the plates for making wiping conductive contact with the plates when the plates are moved toward each other.

5. Switch mechanism comprising a pair of relatively movable conductor plates, and a conductive contact brush comprising a plurality of arcuate laminated brush members bowed in opposite directions and mounted upon a movable support for conductively engaging the conductor plates at the respective ends of the members when the contact plates are moved toward each other.

6. Switch mechanism comprising a pair of relatively movable conductor plates, a guide carried by one of the plates and extending in the direction of movement of the plates, a support mounted for movement upon the guide and movable in the plane of movement of the conductor plates, and a bowed flexible conductor element mounted on the support for conductively engaging the conductor plates with the end edges thereof when the plates are moved toward each other.

In testimony whereof, I have hereunto subscribed my name this 30th day of May 1923.

DAVID REGINALD DAVIES.
